SWINGING SCAFFOLD

Rolph J. Lackner, Richmond Hill, N. Y., assignor
to Emma H. Lackner, Richmond Hill, N. Y.

Application October 7, 1946, Serial No. 701,701

5 Claims. (Cl. 304—19)

1

This invention relates to improvements in swinging scaffolds of the character disclosed in my co-pending application filed August 1, 1946, Serial No. 687,730.

Usually, the free ends of the ropes suspending the scaffold platform are each knotted about the respective hooks of the lower pulley blocks and are so tied in, as it is called, for securing the platform at the level desired. However, the knots mentioned often become loosened or untied, for one reason or another, or are carelessly tied initially, with consequent disastrous results. Furthermore, repeated knotting of the ropes tends to break the fibers thereof and thus shortens the period of usefulness thereof.

The objects of the present invention therefore, in addition to the objects set forth in my pending application mentioned, are to provide a construction wherein the free ends of the ropes suspending the scaffold platform may be safely secured without knotting the ropes, wherein the free ends of the ropes may be so secured without injury thereto, wherein rope clamps each having a fixed and movable jaw will be provided in conjunction with the suspending ropes, wherein the movable jaw may, by means of a locking mechanism therefor, be manually shifted to clamp the strands of a rope between the jaws, when the movable jaw will be held locked in such position to forestall, in so far as possible, any element of carelessness in securing the free ends of the ropes as well as prevent falling of the scaffold platform at either one end or the other thereof should a strand of one of the ropes break, thus to avoid ensuing accident to the workmen on the platform, and wherein said locking mechanism will be so formed that should a strand of either rope break at a time when the strands of the ropes are released and the platform is being raised or lowered, the clamps will be automatically caused to grip said strands and prevent the fall of either end of the platform.

Other and incidental objects of the invention will appear during the course of the following description, and in the drawings:

Figure 1 is a front elevation of my improved scaffold.

Figure 2 is a perspective view of one of the rope clamps employed.

Figure 3 is a plan view of the clamp.

Figure 4 is an end elevation of the clamp.

Figure 5 is a section on the line 5—5 of Figure 3.

Figure 6 is a section on the line 6—6 of Figure 4.

The structure of the present invention is, in large part, the same as disclosed in my prior

2

application previously identified, and it is therefore unnecessary herein to again go into all the details thereof. However, sufficient explanation will be made to render the present improvements clear.

Referring more particularly to Figure 1 of the drawings, I employ the usual platform 10 having rungs 11 supporting a floor 12. Conventional stirrups 13 embrace the platform and are provided at their upper ends with eyes 14 as well as with the usual loops 15 which latter removably receive a guard rail 16. Beams 17 project over the roof or other portion of the building against which the scaffold is erected, as will be well understood, and detachably connected therewith are upper pulley blocks 18 which receive ropes 19 trained about lower pulley blocks 20, the usual hooks 21 of which latter are detachably engaged through the eyes 14 of the stirrups 13 for supporting the platform 10 suspended. Suitably fixed to the blocks 20 are rope clamps, now to be described, but as the parts seen at the right and left of Figure 1 are the same, only a single block and associated parts need be taken up in detail.

Referring now more particularly to Figures 2 to 6 of the drawings, each of the rope clamps mentioned includes a shank 22 which may be integral with the sheath of its supporting block 20 or appropriately attached thereto, and formed on the shank at its upper end is a yoke 23 below which is a laterally extending fixed jaw 24 having spaced fingers 25.

Pivoted upon the yoke 23 is a movable jaw 26 confronting the fixed jaw, and extending laterally from the movable jaw is an arm 27 from which rise lugs 28 fitting between the arms of said yoke. Extending from between the lugs 28 is an operating lever 29, and detachably connecting said lugs and the arm with the yoke 23 is a pivot bolt 30 mounting the movable jaw 26 to rock on said yoke. Adjustable through the free end of the arm 27 is a set screw 31.

Detachably fixed to the ends of the jaw 26 are fingers 32 which extend across the ends of the jaw 24 and cooperate with the fingers 25 to partition the space between the jaws. Thus, as seen in Figures 3 and 6, the strands of the coacting rope 19 may not become entangled at the rope clamp.

Detachably fixed to the rung 11 at the adjacent end of the platform 10 is a collar 33, and extending between said collar and the free end of the lever 29 is a linearly adjustable connecting rod 34 preferably formed of mating detachably connected sections.

As will now be seen, should a strand of one of the ropes 19 break, the platform 10 will move down at the adjacent end thereof and so pull downwardly on that one of the levers 29 connected thereto, with the result that the movable jaw 26 of the associated rope clamp will be rocked toward the fixed jaw 24 of said clamp to bind the strands of the rope between the jaws. Thus, the platform will be automatically prevented from swinging to vertical position. Further, as will be seen, the closing throw of the movable jaw 26 may be roughly adjusted by lengthening or shortening the connecting rod 34, while a finer adjustment of said throw may be had by turning the set screw 31.

Associated with the movable jaw 26 is a locking mechanism therefor. In the present instance, I have shown the shank 22 bent near its upper end to provide a laterally extending yoke 35, and suitably fixed in the mouth of said yoke is an end plate 36. However, the yoke may be formed as a separate part and attached to the shank, in which event the plate 36 will not be necessary. Journaled through the outer end of the yoke and through said plate is a screw shaft 37 upon the outer end of which is fixed a hand wheel 38, and screwed upon said shaft is a cross-head 39 slidably fitting between the sides of the yoke. Thus, as the hand wheel is turned, the crosshead will shift within the yoke. As best seen in Figure 6, said cross head is provided with aligned trunnions 40.

Depending from the arm 27 at the plane of the lugs 28 is a transverse lug 41 which, as will be presently seen, serves as a lever, and extending through said lug is a removable pin 42. Extending between said pin and the trunnions 40 of the crosshead 39 are links 43, and formed in the forward ends of said links are slots 44 which slidably accommodate the ends of the pin.

As will now be appreciated, the hand wheel 38 may, after the platform 10 has been raised to the desired level, be turned for shifting the crosshead 39 outwardly in the yoke 35 and so rocking the movable jaw 26 toward the fixed jaw 24 to active position binding the strands of the coacting rope 19 between the jaws. Thus, the free end of the rope, along with the other strands thereof, will be safely secured between the jaws while, also, the movable jaw will be locked in active position. Accidental release of the free end of the rope will thus be prevented. Furthermore, should one of the strands of the rope break, the platform 10 will be prevented from swinging down at the adjacent end thereof.

By turning the hand wheel 38 in a direction opposite to that first described, the crosshead 39 may be shifted inwardly within the yoke 35 for releasing the movable jaw 26 so that the coacting rope 19 will be free to be employed for either raising or lowering the platform 10. If, during either operation, one of the strands of the rope should break, the adjacent end of the platform 10 will start to move down, with the result that the movable jaw 26 will, as previously described, be actuated by the lever 29 for automatically swinging the movable jaw toward the fixed jaw 24 and binding the strands of the rope between the jaws. The platform will accordingly be prevented from falling. As the movable jaw is thus rocked, through the medium of the lever 29, toward the fixed jaw, the slots 44 in the links 43 will accommodate travel of the ends of the pin 42 relative to said links so that the movable jaw may be freely actuated automatically.

Having thus described my invention, what I claim is:

1. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws and the lever from a pulley block of the scaffold, a connection between the free end of said lever and an end of the scaffold platform whereby dropping of said end of the platform will cause actuation of the movable jaw to grip the suspending rope between said jaws, and locking mechanism for the movable jaw carried by said means and operable to lock said movable jaw in position clamping the rope between the jaws, said mechanism including an element operatively coupled with the movable jaw and manually operable to swing the movable jaw toward the fixed jaw independently of said lever and clamp the rope between the jaws.

2. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws and the lever from a pulley block of the scaffold, a connection between the free end of said lever and an end of the scaffold platform whereby dropping of said end of the platform will cause actuation of the movable jaw to grip the suspending rope between the jaws, locking mechanism for the movable jaw carried by said means and operable to lock said movable jaw in position clamping the rope between the jaws, said mechanism including an element operatively coupled with the movable jaw and manually operable to swing the movable jaw toward the fixed jaw independently of said lever and clamp the rope between the jaws, and a connection between said element and the movable jaw embodying means to accommodate actuation of the movable jaw by said lever while the movable jaw is spaced from the fixed jaw to free said rope.

3. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively coact with said movable jaw for rocking the same toward the fixed jaw to clamp said rope therebetween, means for supporting said jaws and the lever from a pulley block of the scaffold, a connection between the free end of said lever and an end of the scaffold platform whereby dropping of said end of the platform will cause actuation of the movable jaw to grip the suspending rope between said jaws, locking mechanism for the movable jaw carried by said means and including a manually rotatable screw shaft, a crosshead screwed on said shaft and shiftable by turning the shaft, and a connection between said crosshead and the movable jaw operable as the crosshead is shifted for swinging the movable jaw toward the fixed jaw independently of said lever and clamping the rope between the jaws.

4. A safety device for swinging scaffolds including a fixed jaw and a movable jaw disposed at opposite sides of the scaffold suspending rope and normally free thereof, a pivoted lever movable upwardly away from the movable jaw independently thereof and downwardly to operatively contact with said movable jaw for rocking the same toward the fixed jaw to clamp said rope therebetween, means for supporting said jaws and the lever from a pulley block of the scaffold, a connection between the free end of said lever and an end of the scaffold platform whereby dropping of said end of the platform will cause actuation of the movable jaw to grip the suspending rope between said jaws, locking mechanism for the movable jaw carried by said means and including a manually rotatable screw shaft, a crosshead screwed on said shaft and shiftable by turning the shaft, and a connection between said crosshead and the movable jaw operable as the crosshead is shifted for swinging the movable jaw toward the fixed jaw independently of said lever and clamping the rope between the jaws, said last mentioned connection embodying means to accommodate actuation of the movable jaw by said lever while the movable jaw is spaced from the fixed jaw to free said rope.

5. A safety device for swinging scaffolds including a fixed jaw and a movable jaw disposed at

opposite sides of the scaffold suspending rope and normally free thereof, a pivoted lever movable upwardly away from the movable jaw independently thereof and downwardly to operatively contact with said movable jaw for rocking the same toward the fixed jaw to clamp said rope therebetween, means including a shank for supporting said jaws from a pulley block of the scaffold, a connection between the free end of said lever and an end of the scaffold platform whereby dropping of said end of the platform will cause actuation of the movable jaw to grip the suspending rope between said jaws, a yoke carried by said shank, a manually adjustable screw shaft journaled upon said yoke, a crosshead screwed on said shaft and shiftable in said yoke as said shaft is rotated, a lug carried by the movable jaw, a pin carried by said lug, and links connecting the crosshead with said pin at opposite sides of said lug and operable as the crosshead is shifted for swinging the movable jaw toward the fixed jaw independently of said lever and clamping the rope between the jaws, said links being provided with slots receiving the ends of the pin and adapted to accommodate actuation of the movable jaw by said lever while the movable jaw is spaced from the fixed jaw to free said rope.
